UNITED STATES PATENT OFFICE.

JEANETTE JACOBS, OF BOSTON, MASSACHUSETTS.

DESIGN FOR A CHOPPING-KNIFE.

SPECIFICATION forming part of Design No. 31,436, dated August 22, 1899.

Application filed July 29, 1899. Serial No. 725,545. Term of patent 7 years.

To all whom it may concern:

Be it known that I, JEANETTE JACOBS, a citizen of the United States, residing at Boston, in the county of Suffolk and State of Massachusetts, have invented and produced a new and useful Design for a Chopping-Knife, of which the following is a full, clear, and exact description, reference being had to the drawing, which fully illustrates my design.

10 The leading feature of my invention resides in the peculiar shape of the blades, which are united by an arch-shaped yoke, to which the handle and shank are connected.

Referring to the drawing, A indicates the 15 chopping-blades, which are rounded, as at A', at their outer ends and beveled or inclined at their inner ends, as shown at A². An arch-shaped yoke B connects the inner ends of the

blades, and at the center of said yoke a shank C projects upwardly therefrom and to which 20 the handle B is attached.

By means of a chopping-knife constructed in accordance with this design the chopping of meat and similar articles can be accomplished much easier than with the ordinary 25 form of chopping-knife now in use.

Having thus fully described my invention, what I claim as new, and desire to secure by Letters Patent of the United States, is—

The design for a chopping-knife, substantially as shown and described.

JEANETTE ^{her} X JACOBS.
